209,379

END PLUG FOR A CONDUIT OR THE LIKE

William G. Quick, 8919 E. Wedgewood St.,
Los Angeles, Calif. 90028

Filed Dec. 8, 1966, Ser. No. 4,971

Term of patent 14 years

(Cl. D91—3)

FIGURE 1 is a top plan view of a cap for an end plug for a conduit or the like showing my design;

FIG. 2 is a front elevational view thereof;

FIG. 3 is an elevational view taken from the right side thereof; and

FIG. 4 is a bottom plan view thereof.

I claim:

The ornamental design for an end plug for a conduit or the like, substantially as shown.
